Inventor:

Ellsworth E Flora

Rey. Emry Borle Farnay & Farnay

UNITED STATES PATENT OFFICE.

ELLSWORTH E. FLORA, DECEASED, LATE OF CHICAGO, ILLINOIS; BY LUELLA B. FLORA, EXECUTRIX, OF CHICAGO, ILLINOIS, ASSIGNOR TO SIGNODE SYSTEM, INCORPORATED, OF CHICAGO, ILLINOIS, A CORPORATION OF DELAWARE.

APPARATUS FOR APPLYING BINDERS TO BOXES AND PACKAGES.

Application filed March 17, 1919. Serial No. 283,207.

To all whom it may concern:

Be it known that ELLSWORTH E. FLORA, deceased, late a citizen of the United States, residing at Chicago, in the county of Cook 5 and State of Illinois, did invent an Improvement in Apparatus for Applying Binders to Boxes and Packages, of which the following is a specification.

This invention relates to devices for applying tensional binders to boxes, packages, or the like. It is the purpose of the invention to provide a device of the character described, simple in construction and easy and efficient in operation.

15 In the illustrative embodiment of the inventions disclosed in the accompanying drawings, the device takes the form of a hand tool adapted to operate upon flat tensional box-strapping, to stretch this box-strapping about a box or package with its ends mutually overlapped and thereafter to join the overlapped ends by forming therein a simultaneous crimp of the character disclosed in the patent to Flora No. 1,038,108, 20 dated September 10, 1912.

It being understood that the drawings disclose an illustrative embodiment merely of the invention, and that the latter is not confined to the specific form shown in the 25 drawings: Fig. 1 is a side elevation of an appliance constructed in accordance with my invention. Fig. 2 is a front elevation thereof. Fig. 3 is a sectional elevation thereof on the line 3—3, of Fig. 2. Fig. 4 is a sectional elevation on the line 4—4, of Fig. 3. Fig. 5 is a view similar to Fig. 4, showing the parts in another position. Fig. 6 is a 35 sectional elevation on the line 6—6, of Fig. 3.

40 In Figs. 2 and 3; the hand tool is shown as in operation upon a box strap applied about a box or package whose overlapped ends 1 and 2 have been brought into cooperative relation with the tool.

45 For clarity of description I shall first describe separately the two essential functioning parts of the tool, referring only to their more important operating elements, and then describe in detail the construction of 50 the tool and the cooperative relationships of the elements thereof.

The means for stretching or tensioning the strap comprise essentially feed wheel 3, hav-

ing a pair of knurled strap gripping rims 4, which feeds forward the top overlapped strap end 2, the end sliding longitudinally along the bottom overlapped strap end 1 which is maintained in relatively stationary position by a suitable stationary clutch plug 5 engaging the lower face. This operation 60 continues until the required degree of tension is placed the top strap end 2 being forced to the left (Fig. 3) while the bottom end 1 is maintained relatively stationary with respect to the tool by the plug. 65

70 Cooperatively associated with the stretching mechanism and adapted to act upon the overlapped portions of the strap ends presented in appropriate position by the stretching mechanism, is a strap joining element. Thus I provide a pair of crimping jaws 6, operating in combination with a centering device or chair 7, which serves to form a simultaneous crimp in the overlapped strap ends, as presented by the stretching elements, connecting the strap ends securely 75 together.

77 It will be apparent from an inspection of Fig. 1 that the central stationary element or base of the tool comprises a heavy integral structure U-shaped in cross section having a pair of vertical side pieces 19 with which is integrally formed the handle 10. This supports all of the operating parts of the tool. Below the handle 10 is mounted an operating handle 11 for the stretching elements of the appliance; and above it is mounted the operating handle 12 for the strap joining elements. Thus the two main functioning elements in the tool, may be operated alternately without changing the position of the tool, the operator for the stretching operation, squeezing the handle 11 toward the stationary handle 10; and for the sealing operation, releasing handle 11 and grasping and squeezing the other pair of handles, namely handles 10 and 12.

80 I will now describe more particularly the precise mechanical construction of the embodiment of the tool represented in the drawings: The feed wheel 3 is provided between the knurled rims 4 with a recess in which are formed ratchet teeth 15 by means of which the feed wheel is intermittently rotated. A detent pawl 16 mounted upon pin 18 in the vertical side 19 of the tool and 85

held to its duty by the spring 17 serves to maintain the feed wheel against slipping back.

In order to drive the feed wheel 3 forward, I pivot the handle 11 on the pin 20 carried in lugs 21 extending downwardly from and integral with the stationary handle 10, and employ a pawl 22 inside of the handle 11. The pawl 22 is held to its duty by the spring 23 and a coil spring 24 secured to the handle 10 at its upper end, and to the forward end of handle 11 at its lower end, serves to return the handle 11 after each operating stroke. Pins 25 in the handle 11 near its pivot serve to limit the play of handle 11, in either direction, as clearly shown in the drawings.

The feed wheel 3 may move up and down for the purpose of binding the overlapped strap ends against the clutch plug 5 during the stretching operation and to release the strap ends after the stretching and joining operations are finished. For this purpose I provide a shaft 26 provided with an operating handle 27 normally maintained in vertical position under the influence of a spring 28 wrapped around the extending end of the shaft 29 and engaged therewith at one end and with the vertical side of the tool base 19 at the other end. The spring maintains the handle 27 against the stop 29'. The portion of the shaft 26 between the two vertical side pieces of the frame 19, is formed into an integral eccentric 30 upon which the feed wheel 3 is revolvably mounted. The spring 28 holds the eccentric 30 in a position to engage the strap with considerable force; by pulling the handle 27 rearward (to the right, Fig. 1) the feed wheel 3 can be raised to release the strap.

As a bottom support for the strap during the stretching operation, I provide the extended angle piece 32, the vertical flange of which is rigidly mounted to one of the vertical side pieces 19; the horizontal portion of the piece 33 serves as a foot or rest for the entire tool and carries the clutch plug 5. The foot 33 is tapered at its outer edge as indicated at 34 and in effect provides a slot between the foot 33 and the feed wheel 3 into which the overlapped strap ends are inserted when the tool is slipped sideways upon them. The foot 33 is smooth on its bottom face to permit sliding on the surface of the box.

The side frames 19, extend forwardly as indicated at 36, and are provided at their forward upper ends with upstanding lugs 37 through which is passed the screw pin 38 which forms a pivot for the handle 12, the latter being hollowed out adjacent to this pivot and provided with the ears 39 surrounding the pin 38.

The handle 12 as above stated is the operating handle for the crimping or sealing jaws and for this purpose is provided for-

ward of the pivot pin 38 with a wedge-shaped cam 42 which operates between the rounded noses 43 of screws 44 carried at the upper ends of the pivoted crimping jaws 6.

The crimping jaws 6 are held against the cam 42 by the tension spring 45 and rock on a common pivot bolt 50, provided at its rearward end with a reduced extension 51 which is threaded into the block 52, seated between forward extensions 36 of the pieces 19. The jaws 6 are mounted on the bolt 50 by means of two pairs of integrally formed overlapping concentric spaced ears 53 which are revolvably mounted on the bolt 50 (see Fig. 3).

At their lower ends the crimping jaws 6 are each provided with an inwardly projecting flange 55 forming a rounded edge as clearly indicated in Fig. 3; and centrally in the lower part of each jaw just above the flange 55, is mounted a pin 56 the inward edge of which 57 in combination with the edge 58 of the jaws 6 serves to effect the simultaneous crimping of the box strapping into a tight joint when the jaws are strongly forced together by the operation of the handle 12. The screws 59 are let into the crimping jaws 6 to maintain the pins 56 firmly in position.

In order to form a uniform and correct crimp joint in the overlapped box strap ends, I provide a chair device 7 (previously alluded to) which constitutes a forward integral extension of the block 52 which is firmly riveted between the side pieces of the frame 19 and thus affords an absolutely rigid backing for the crimp joint. The chair device 7 is provided with an integral upwardly extending lug 62 which snugly encircles the bolt 50 between the ears 53. Thus the bolt 50 is maintained by being screwed firmly into the block 52 at its inner end, and between the paired lugs 53 is additionally supported by the rigid lug 62 which is of one piece with the block 52. This makes an exceedingly strong construction.

Upon reference to Fig. 1, it will be observed that the structure is made additionally stable by providing the block 52 with shoulders 63 just behind the rear edge of the crimping jaws against which shoulders the vertical side pieces 19 of the base squarely abut.

In operation the tool may easily be applied to overlapped box strapping encircling a box or package B by slipping it sideways thereon so as to introduce the strap ends into the slot between the foot 33 and the feed wheel 3 shown in Fig. 6. When in this position of the parts the crimping jaws 6 which are normally held apart by the action of the spring 45 lie flush with the median plane of the overlapped strap ends ready to move inward to seize the same and perform a crimping operation thereon whenever the operator desires. The operator next releases

the handle 27, which it is understood has been drawn back to separate the feed wheel 3 and clutch plug 5 so as to engage the overlapped ends firmly between the clutch plug 5 and the feed wheel 3; and repeatedly squeezes the handle 11 toward the handle 10. This operation tensions the strap about the box or package to whatever degree desired. Next the operator releases the handle 11, and by grasping the handles 12 and 10 and squeezing these handles together joins the strap ends together. Thereupon by releasing the handle 12 and drawing back the eccentric handle 27 the tool may be slipped sideways off the box strap ends leaving behind it a binder both stretched and joined about the package.

What is claimed is:

1. In a tool for applying box binders to boxes or the like stretching means comprising a binder engaging element, a lever for operating said binder engaging element to stretch the binder; binder end joining means comprising a lever, a support for said means, and a common backing handle adapted to be utilized with and in the operation of either lever independently of the other.
2. In a tool of the class described, a support, a shaft carried by said support, a pair of opposed levers pivotally mounted upon said shaft at points intermediate their ends, said levers being provided at their lower ends with crimping jaws, and at their upper ends with wedge engaging screws, a wedge disposed between said screws, a lever for operating said wedge, and spring means normally holding the screws against said wedge.
3. In a tool of the class described, a support, a pair of levers pivotally mounted on said support, said levers being provided at their lower ends with jaws, and a lever for actuating said pair of levers to force said jaws toward each other.
4. In a tool of the class described, a support, a pair of levers pivotally mounted intermediate their ends on said support, said levers being provided at their lower ends with jaws, an operating lever, and means actuated by said operating lever for forcing the upper ends of the levers of said pair from each other.
5. In a tool of the class described, a support, a pair of opposed levers pivotally mounted on said support at points intermediate their ends, said levers being provided at their lower ends with co-operating jaws, a wedge disposed between the upper ends of said levers, and an actuating lever for operating said wedge to force the upper ends of said levers from each other.
6. In a tool of the class described, a support, a pair of opposed levers pivotally mounted on said support at points intermediate their ends, said levers being pro-
- vided at their lower ends with co-operating jaws, a wedge disposed between the upper ends of said levers, an actuating lever for operating said wedge to force the upper ends of said levers from each other, and spring means normally forcing the upper ends of said levers toward said wedge.
7. In a tool for applying flat tensional binders to boxes or the like, a support, means on said support operable to stretch a flat tensional box binder about a box or package, a lever for operating said means, means for crimping the overlapped ends of the binder together to form a tension resisting joint, a lever for operating said last-mentioned means, and a common backing handle fixed to said support and adapted to co-operate with said first and second-mentioned levers successively in the operation of the tool.
8. In a tool for tensioning a flat binder about a package and uniting the overlapped ends thereof, rotatable means arranged to frictionally engage one end of the binder to tension said binder upon rotation of said means, and means for forming a tension resisting joint in the overlapped binder ends, said first mentioned means being arranged to maintain tension in said binder during the operation of said second-mentioned means.
9. In a tool for tensioning a flat binder about a package and uniting the overlapped ends thereof, a support, rotatable means on said support arranged to frictionally engage one end of a binder to tension said binder upon rotation of said means, a lever for rotating said rotatable means, means for forming a tension resisting joint in the overlapped binder ends, a lever for operating said second mentioned means, and a common backing lever adapted to co-operate with said first and second mentioned levers successively in the operation of said tool.
10. In a tool for tensioning a flat binder about a package and uniting the overlapped ends thereof, a support, rotatable means on said support arranged to frictionally engage one end of said binder to tension said binder upon rotation of said means, a lever to rotate said rotatable means, a pair of opposed levers pivotally mounted on said support, said levers being provided with crimping jaws at their lower ends, a second lever for operating the levers of said pairs to force said jaws toward each other, a common backing lever fixed to said support and adapted to co-operate with said first and second mentioned levers successively in the operation of said tool.
11. In a tool for tensioning a flat binder about a package and uniting the overlapped ends thereof, a support, rotatable means on said support arranged to frictionally engage one end of said binder to tension said

binder upon rotation of said means, a lever for rotating said rotatable means, a pair of opposed levers pivotally mounted at points intermediate their ends on said support, said levers being provided at their lower ends with crimping jaws, a wedge disposed between the levers of said pair, an operating lever for actuating said wedge to force the upper ends of the levers of said pair from

each other, and a common backing lever 10 fixed to said support and adapted to co-operate with said first and second mentioned operating levers successively in the operation of said tool.

In testimony whereof I have signed my 15 name to this specification.

LUELLA B. FLORA,
Executrix of Ellsworth E. Flora, deceased.
